WELL CEMENTING APPARATUS

Original Filed June 8, 1940

4 Sheets-Sheet 4

Fig. 11.

A cross-sectional view of a vertical cylinder assembly. The central vertical structure is labeled 34. At the top, a horizontal component is labeled 90. Below it, a vertical component is labeled 91. The main vertical structure is labeled 36. A horizontal band near the bottom is labeled 35. At the very bottom, a component is labeled 34'. The assembly is surrounded by a hatched outer boundary. Various other labels are present: 46, 43, 44, 40, 41, 38, 37, 37a, and 46'.

1920-1921

Fig. 9.

Fig. 12.

A technical drawing of a cylindrical component. The top surface features a circular hole. The lower portion of the cylinder is divided into two sections: a central vertical column and two flanking sections. The central column is unshaded, while the flanking sections are filled with a diagonal cross-hatch pattern. A dimension line with arrowheads spans the width of the flanking sections, labeled '77'. A dimension line with arrowheads spans the height of the central column, labeled '80'.

4 Claims. (Cl. 166—1)

1

This invention relates to new and useful improvements in well cementing apparatuses.

One object of the invention is to provide an improved well cementing apparatus including a member having a passage therethrough with back pressure means for closing off said passage and means for selectively anchoring and packing off said member in a well, together with a cementing tube adapted to be inserted and withdrawn from said member and self closing means on the lower end of the member arranged to be opened by the cementing tube, whereby the lower end of the passage is closed when the tube is withdrawn.

Another object of the invention is to provide an improved well cementing apparatus including an anchoring and packing member adapted to be located in a well and carrying an elastic self closing boot at its lower end; together with a cementing tube arranged to pass through the packing in said member, as well as, through said boot, whereby said boot closes when the tube is withdrawn.

A construction designed to carry out the invention will be hereinafter described together with other features of the invention.

The invention will be more readily understood from a reading of the following specification and by reference to the accompanying drawing, wherein an example of the invention is shown, and wherein:

Figure 1 is a vertical sectional view showing the anchoring mechanism set in the casing with its pendant cementing valve assembly.

Figure 2 is a similar view through the cementing valve assembly showing the cementing tube in preliminary washing or cementing position.

Figure 3 is another similar view showing the anchoring mechanism, cementing valve assembly and cementing tube with the latter partially retracted as in applying pressure to the cement.

Figure 4 is still another similar view showing the parts of Figure 3 in position to cleanse the cementing valve assembly and anchoring mechanism for placing them in condition for subsequent retrieval.

Figure 5 is a detail sectional view taken substantially on line 5—5 of Figure 2.

Figure 6 is a detail section through a portion of the cementing valve assembly illustrating a slight modification.

Figure 7 is a sectional view, partly in elevation, showing the retriever in position in connection with the anchoring mechanism ready for withdrawal therefrom.

2

Figure 8 is a side elevation of the retriever equipped for running in of the cementer.

Figure 9 is a detail sectional view showing the use of a protecting device for the anchoring mechanism where the latter and the cementing valve assembly are utilized as a casing plug or bridge.

Figure 10 is a view partly in elevation and partly in section, of a modified retriever for run in on well tubing or drill pipe, and

Figure 11 is a sectional view through the anchoring mechanism in place with a back pressure valve where it is used as a casing bridge or plug only, and

Figure 12 is a detail sectional view showing a slight modification of the protector plug of Figure 9.

Referring now to the above described drawings, the invention contemplates the use of a retrieving means functioning in a manner permitting use thereof as a cement retainer after a cementing operation, and utilizable as a casing plug or bridge in a later cementing operation thereabove, and adaptable to maintenance in and throughout such uses in a condition permitting retrieving and removal thereof as a unit.

In Figure 2 in particular of the drawings there is shown the lower portion of certain of the co-operating parts of the invention in position for a cementing operation in the bore A of the well below the lower end of the well casing B, an elongated tubular cementing point 20 being plainly shown depending from the cementing tube 21 and of somewhat greater external diameter than the latter to snugly, slidably interfit the bore or axial passage 22 of the body 23 of the cementing valve assembly through which the cementing tube 21 passes with substantial clearance. For ease of description but not as a limitation upon the subject matter to be claimed herein the cementing valve assembly will be considered as all of that mechanism or structure which lies below the bushing 34' in Fig. 1 and the anchoring mechanism will be that mechanism or structure which lies above the bushing 34' as shown in the same figure.

As best seen in Figure 1, the body 23 of the cementing valve assembly has within its axial bore 22 pressure rings 24 which cooperate with the cementing point 20 in a manner to effectively close such bore to the upward passage of pressure when the said point is retracted upwardly from the position shown in Figure 2 to the position shown in Figure 3. The valve body 23 also has an upstanding reduced neck portion 25 having a

limited slideable movement through the base of the connecting box 26, below which box 26 and around which neck portion 25 is a series of packing rings 27 which are thus grouped between the base of box 26 and the body 23 of the cementing valve assembly which forms an annular shoulder at the lower end of the neck portion 25.

It will be observed that the upper end of neck portion 25 within box 26 has a collar 25' so that the cementing valve assembly as a whole is thus supported by the box in a manner which admits of limited upward movement thereof in the run in position with respect to the box for a purpose which will be presently explained.

It is plain that, as viewed in Figure 1, if the cementing valve assembly is forced upwardly with respect to the connecting box 26 from which it normally hangs, packing 27 will be longitudinally compressed and forced by lateral expansion into tight sealing engagement with the inner surface of the well casing B as seen in Figure 3.

At the lower end of the body 23 is an upwardly seating, spring controlled flap valve 28, normally seated by its spring 29 across the lower end of the bore 22 to effectively close the latter against the upward passage of pressure after withdrawal of the cementing point 20 above the valve as seen in Figure 4. It will be noted at this time that in lowering the cementing point 20 preparatory to a washing and cementing operation, it opens valve 28 downwardly and no matter how far the said point is passed below the cementing valve assembly, said valve 28 is maintained in open position by the cementing tube 21. This is plainly seen in Figure 2.

Secured to the body 23 around its lower end is a hollow depending boot support or form 30, open at both ends within a cylindrical flexible, elastic boot 31 which extends at its upper end around the body 23 and has an inturned flange 32 engaged between the upper shoulder of the body 23 and the packing 27. The lower thickened end portion 33 of this boot extends across the lower open end of its support 30 and is radially slitted to open when the cementing point 20 and tube 21 are lowered through the same to allow free passage of fluid therethrough, as plainly seen in Figures 2 and 5 and is adapted to close when the said point 20 is withdrawn upwardly as may be seen in Figure 4.

Referring again to Figure 1, the cementing valve assembly and its above described parts are supported at the lower end of the anchoring mechanism by virtue of the connection of the top of the box 26 securely on the lower end of the tubular mandrel 34, as for instance by a bushing 34'. The said bushing 34' at the top of the box 26 around the lower end of mandrel 34 forms a rest for the lower end of a spring 35 disposed around the mandrel beneath the collar 36, having an annular series of slips 37 having spring supporting arms upstanding from said collar around the mandrel and in engagement with a downwardly tapering slip expander 38 which seats at its lower end on an external shoulder 39 of the mandrel.

The upper end of mandrel 34 is threaded into a coupling 40, and supports a surrounding packing 41 thereon between said coupling and the upper larger end of the expander 38, which packing may be compressed longitudinally, and in this way expanded laterally into sealing contact with the casing B when the mandrel is forced downwardly through expander 38 after the slips 37 have been

set to hold the said expander against downward movement.

The coupling 40 has a series of radial openings 42 through its wall extending from its bore which coincides with the bore of the mandrel 34 below the same, and also with the bore of the tubular mandrel extension 43 secured to and extending above the coupling in line with the mandrel 34. The coupling 40 also has an annular series of spring supporting arms upstanding therefrom and carrying slips 44 seated around the lower downwardly tapering or expander portion 45 of an upper tubular barrel 46 which is slideable lengthwise of the mandrel extension 43.

It will be noted that the mandrel extension 43 has openings 47 radially through its wall immediately above the coupling 40 and also similar openings 48 adjacent to its upper end, below its head 49 which latter is engageable with an internal upwardly facing shoulder 50 of the barrel 46 so as to limit upward movement of the latter with respect to the mandrel extension.

For the purpose of allowing cooperation of the retrieving means, to be presently described, with the barrel, the latter as best seen in Figure 7 has an annular groove 51 in its internal surface at a point spaced a short distance from its upper end which latter is conically counterbored as at 52. The groove 51 forms at its ends annular shoulders of which the upper downwardly facing shoulder is indicated at 53, and the lower shoulder at 53'.

All of the above described assembly including the anchoring mechanism with its slips 37 for holding against downward displacement and its packing 41 and slips 44 for holding against upward displacement, as well as the cementing valve assembly carried as before described on the lower end of the anchoring mechanism, may be lowered into the casing B on a wire line 54 by virtue of a retriever shown in Figures 7 and 8, to the upper end of the upper lowering stem 55 of which the line 54 is connected.

The lowering stem 55 is slideable through the collar 56 fixed on the upper end of a slotted jar sleeve 57 and has a head 58 at its lower inner end opposing a similar head 59 on the upper end of a lower clutch stem 60 which is slideable through a collar 61 fixed on the lower end of the sleeve 57. It will be understood that collar 56 limits upward movement of the head 58 of the lowering stem and collar 61 limits downward movement of head 59 and that the relative lengths of these parts are such that when the clutch stem 60 is in engaged relation with the anchoring member, collar 61 on the lower end of sleeve 57 may be lowered into contact with the upper end of the barrel 46 as in Figure 7 and the stem 55 may be lowered to a point where its head 58 will engage the clutch stem head 59 as shown in the same figure.

The clutch stem 60 has a lower reduced shank 62 terminating at its lower end in a spear head 63 and forming at its upper end a downwardly facing annular shoulder 64 which, in the lowering position of the retriever parts as seen in Figure 8, is positioned some distance below the lower end of the jar sleeve collar 61. The spear head 63 has an axially depending reduced pilot stem 65 detachably connected thereto and preferably in the nature of a hollow perforate tube, and said stem is of a length sufficient to extend downwardly through the anchoring mechanism and cementing valve assembly, when the spear head 63 is in the upper portion of the barrel 46 as in

Figure 7, to press flap valve 28 downwardly to open position as well as open boot end 33 so that the stem 65 may be lowered into fluid in the casing B without trouble.

Normally loosely disposed on and around the shank 62 of the clutch stem 60 is a clutch sleeve 66 shiftable lengthwise thereof above the spear head and provided with upper and lower annular series of clutch balls 67 and 68 disposed in conical wall openings which permit the balls to protrude beyond the external surface of the sleeve and into the barrel groove 51. At its upper end, sleeve 66 has an annular series of upstanding inwardly inclined spring fingers 69 grouped loosely around the shank 62 of the clutch stem 60 and adapted to snugly frictionally grip the latter above shoulder 64 when the said stem is forced downwardly into the clutch sleeve beyond its normal clutched position as hereinafter seen.

Within the sleeve 66, the shank 62 has upper and lower annular grooves 70 and 71, forming between them an annular rib 72 which, when opposite to either of the series of balls 67 and 68, serves to hold such series in outer clutched position, permitting the other series to retract or move inwardly to unclutched position in one of the grooves 70, 71.

Thus with the clutch sleeve 66 loosely supported on the shank 62, the spear head 63 preceded by its pilot stem 65 may be extended into the barrel 46, with the annular rib 72 of the shank opposite the upper balls 67 and the lower portion of sleeve 66 resting on the spear head 63. When sleeve 66 enters the barrel to a point where the upper balls cannot pass the barrel end, further inward movement of said sleeve is arrested until the shank 62 has been moved inwardly with respect thereto sufficiently to shift its rib 72 downwardly beyond the balls 67, thus permitting the latter to move into the shank groove 70 whereupon the sleeve may continue its movement into the barrel to fully clutched position from which it cannot be withdrawn as long as the sleeve 66 is loose on the shank 62.

With the retriever thus coupled to the anchoring mechanism, the retriever, anchoring mechanism, and cementing valve assembly all as a unit may be lowered on the line 54 into the casing and downwardly to the point at which it is desired to effectuate the cementing operation as, for instance, adjacent to the lower end of the casing B for cementing the formation in the well bore A as indicated in Figure 2. Bear in mind that during the run in the pilot stem 65 of the retriever extends downwardly through the anchoring mechanism and cementing valve assembly and holds the flap valve 28 open so that no difficulty will be encountered in the run in because of fluid in the well bore and casing.

When lowering the above assembly into a well, it is to be understood that slips 37 are positioned at the lower end of the expander 38, the spring arms 37a, by which these slips are supported in upstanding relation on collar 36, being preferably integral at their lower ends with said collar and being tensioned to urge the group of slips inwardly against the smaller end of the expander and away from the well casing B. It is also to be understood that in its position of the parts, the collar 36 is floatingly supported on spring 35, with the latter partially compressed by reason of the weight of the collar and the group of slips 37. At this time the upper tubular barrel 46 is in its upper position and the upper slips 44, supported on short powerful spring arms 44a, preferably

integral with, and upstanding from, the coupling 40, are held closely grouped around the lower smaller end of the lower tapering portion 45 of the barrel 46, and thus in a position spaced inwardly from the well casing B.

With the parts in the above described initial position, the assembly is lowered into the well casing in a steady movement, to thus avoid any tendency toward substantial vertical vibration of the collar 36 on its partially compressed supporting spring 35 above the bushing 34.

When, however, the point has been reached, in the run in of the assembly, at which it is desired to set the anchoring mechanism, the lowering movement is accelerated and then suddenly stopped, or after a pause in the steady lowering movement, the assembly may be raised slightly and then suddenly lowered and similarly checked. In either event accelerated lowering movement and sudden stopping of the assembly results in causing the collar 36 and its slips 37 to move forcibly, downwardly by inertia toward the bushing 34' so that the supporting spring 35 is further, and substantially fully, compressed. In the immediately following reaction, the expansion of spring 35 shifts the collar 36 and its slips 37 forcibly, upwardly to a point where the slips 37, riding upwardly on the tapering surface of the expander 38, are spread laterally into gripping engagement with the inner surface of the wall of casing B, to thus lock the anchoring mechanism and cementing valve assembly against further downward movement. At the same time the supporting and lowering line 54 is slackened off so that the weight of the assembly is effective to hold the slips 37 in casing gripping position.

At this time the several parts of the retriever are extended as shown in Figure 8 and the upper slips 44 are closely grouped under control of their spring arms 44a, around the lower end of the lower tapering expander portion 45 of the barrel 46. As soon as the slips 37 are set, further lowering of the line 54 permits the relatively movable jar sleeve 57 to be dropped so that its lower collar 61 seats on the upper end of the barrel 46 and the head 58 of lowering stem 55 engages the upper head 59 of clutch stem 60, as shown in Figure 7. Then by alternate upward and downward movements of the line 54, under control from the surface, the clutch stem 60 may be hammered or spudded downwardly. During the initial downward movement of the clutch stem 60, connected to barrel 46 through clutch sleeve 66, the said barrel is shifted downwardly on the mandrel extension 43 a short distance sufficient to permit its tapering lower portion 45 to expand the upper slips 44 into engagement with the inner surface of the casing B, to thus lock the assembly against subsequent upward displacement under well pressure. It is to be understood, however, that when so engaged, the slips can further move in a downward direction due to the upward inclination of their teeth. Following the slight initial downward movement of the barrel 46 on mandrel extension 43, the lower spear head 63 of the clutch stem 60 engages the upper head 49 of mandrel extension 43, and in the further downward spudding of the clutch stem 60, the mandrel extension 43, coupling 40, slips 44, mandrel 34 and barrel, all move downwardly with respect to the packing 41 which is held against downward movement by the expander 38 which is securely held at this time by the engaged slips 37. Thus the packing 41 will be compressed immediately following the setting of the slips 44, and will be held com-

pressed until such time as the barrel 46 is shifted upwardly relative to the mandrel extension 43 to permit the slips to spring inwardly away from the wall of the casing B.

It will be plain by reference to Figure 7 that the above setting of the anchoring mechanism in place within the casing B against movement longitudinally of the latter, that is, against either upward or downward movement therein, leaves the retriever in substantially the position of Figure 7, ready for withdrawal, this being the next operation, preparatory to the introduction of the cementing tube and its point, since we now have the anchoring mechanism positioned in the casing as shown in Figure 1 with the cementing valve assembly freely depending therefrom in the casing. Figure 7 shows the shank 62 forced downwardly through clutch sleeve 66, resting on shoulder 53', until its rib 72 is opposite the lower balls 68 and its upstanding fingers 69 have been spread apart by shoulder 64 and are in snug frictional engagement with the clutch stem 60 above said shoulder.

Thus upon raising the line 54 the retriever starts upward and in this movement the clutch sleeve 66 follows along with the clutch stem 60 until the upper balls 67 pass above the upper end of barrel 46 and the lower balls 68 engage the upper internal shoulder 53. At this point the sleeve is arrested and further upward movement of the clutch stem pulls its shank 62 upwardly through, and relative to, the clutch sleeve 66, until its rib 72 moves upwardly past the lower balls 68 whereupon the latter are free to recede inwardly within groove 71 and thus permit the retriever to be drawn completely free of the anchoring mechanism with its parts in position to be lowered into effective engagement therewith at any time.

Following removal of the retriever from the set anchoring mechanism as above described, the cementing tube 21 is run in with its elongated cementing point 20 passing downwardly through the anchoring mechanism and through the cementing valve assembly for opening, and thereafter holding open, the flap valve 28 and the slotted end 33 of the boot 31. It is obvious that in so doing circulation is fully established as shown by the arrows in Figure 2, which pictures the parts in the above position, for the thorough washing of the well bore A and subsequent introduction of cement.

Prior to extension of the cementing point 20 below the cementing valve assembly to establish circulation, it may be desirable to arrest the said point within the cementing valve assembly where it serves, in cooperation with the internal packing rings 24 to close the passage through the packing. Then, by pressure downwardly through the cementing tube 21 and point 20, against the lower end of the body 23, the latter may be forced upwardly with respect to the stationarily held anchor mandrel 34 and box 26 so that, by longitudinal compression of packing 27 between box 26 and body 23, said packing will be laterally expanded into tight sealing engagement with the inner surface of the casing B.

With the packing 27 sealing off the casing B, as shown in Figure 3, the entire space within casing B between this packing and the upper packing 41 will be sealed off against the encroachment of cement, during the subsequent cementing operation, around the lower portion of the anchoring mechanism including the hold down slips 37.

In order to insure that packing 27 will remain expanded and effective upon release of pressure, it may be desirable to provide the base of the box 26 with radial bores, around the reduced neck 25 of the body 23, as shown in the modification, Figure 6. In this case the said neck 25 will have series of ratchet teeth 73 and in each of the above bores of the box base, a pin 74 will be pressed by a spring 75 to engage a series of such teeth, so that when the neck is forced by pressure upwardly into box 26 from the position of Figures 1 and 2 to the position of Figure 3, it will be held against dropping back upon release of pressure. Continued effectiveness of packing 27 is thus assured throughout the cementing operation, but it must be kept in mind that the ratchet pins 74 are of shearable material, since they must be sheared off in withdrawing the apparatus from the well in a manner to be presently described.

With the parts in the before described position of Figure 2, and full circulation established, the well bore A may be thoroughly washed and when this has been accomplished, cement may be pumped into the bore to any desired extent or any desired level. Should this desired level be such as not to reach the lower end of the casing B, the amount of cement may be controlled to bring this about or if such control is not feasible, the cementing tube and point 20 may be drawn upwardly or otherwise positioned so that the lower end of the point 20 is at the desired level and all cement above such point may be then circulated out either through the anchoring mechanism and cementing valve assembly or through the cementing tube. In this way the ultimate upper level of cement may be easily controlled.

Should the cement rise, in the cementing operation, around the boot 31 it can only pass upwardly to the packing 27 and even then washing fluid will be trapped around the boot and prevent effective setting of cement substantially above the lower end of the said boot. However, cement may find its way upwardly into the cementing valve assembly and even into the anchoring mechanism, although when, after the cementing operation has been completed and the cementing tube 21 and point 20 are drawn up to the position of Figure 3, with the point 20 in the cementing valve assembly for the supply of pressure down the cementing tube 21 to force the cement firmly into the formation, the tube and point may then be elevated to the position of Figure 4.

During the last mentioned movement the lower slotted end 33 of boot 31 closes in as the lower end of the cementing point passes above the same so as to thus cut off the bulk of the cement entering the cementing valve assembly, and in this way leaving only thin fillets of cement through the slits of the boot which need be subsequently broken away to withdrawn the anchoring mechanism and cementing valve assembly from the hole. It is thus apparent that the boot 31, in its closing movement, acts as a cement cut off means below and independent of the back pressure valve 28, since its function is to cut off or squeeze off the cement while it is soft, and so reduce the bulk of the cement at this point, that it may be easily broken after the cement has hardened and the tool is to be withdrawn from the well. This boot thus acts, after flow of cement into the well has been stopped, as a shield between that portion of the cement in the well below the boot, and that portion of the cement within the boot and below the back pressure valve 28. Furthermore as the

lower end of the cementing point 20 passes above the flap valve 28, the latter closes by the pressure below the same and upon further upward movement of the cementing point 20 until its lower end is above the sealing rings 24, or in other words, to the position shown in Figure 4, it is obvious circulation is again established and all cement above flap valve 28 may be completely washed and circulated out of the cementing valve assembly, and anchoring mechanism and the vulnerable portions of these parts above the packing 41 may be thoroughly cleansed by virtue of the openings 42 through the coupling 40 and the openings 47 and 48 through the mandrel extension 43.

It should not be overlooked that the parts of my invention as positioned in either Figures 2, 3 or 4, readily lend themselves to reverse circulation by suitably packing off the surface end of the cementing tube 21, so that by circulating down the casing and up through the cementing tube cement can be circulated off from all points above the lower end of the cementing point 20 in any position of the latter where it does not seal the passage through the body 23. Much saving of time can be effected in this way where the cementing operation is checked with a considerable amount of cement in the tube 21, and this is highly important in any instance where time is a factor.

After thorough cleansing as above, the cementing tube 21 and point 20 are withdrawn above the anchoring mechanism and the latter and the cementing valve assembly remain as a cement retainer in the casing to hold the pressure on the cement below flap valve 28 until the cement sets.

It is also a feature of this invention that by using any easily retrievable means such as rubber protecting discs above the cleansed anchoring mechanism, the well bore may be successively cemented off at various stages or points thereabove through shot holes in the casing B, the anchoring mechanism and cementing valve assembly being left as above described to serve as a retainer for cement therebelow and a plug or bridge for cement thereabove at each point so cemented. Then after the cement jobs have set it is only necessary to successively drill out the cement at the various stages within the casing down to the rubber protectors of the next lowermost assembly and remove the rubbers and then retrieve the assembly.

I have shown such an arrangement as above described in Figure 9 where a rubber protecting plug 77 appears on top of the barrel 46, in an instance in which the anchoring mechanism and cementing valve assembly are utilized not only as a cement retainer for a cementing job below the same, but as a casing plug or bridge for a succeeding cementing job thereabove. The protecting plug 77 is preferably formed with an insert 78 presenting a longitudinal bore 79 which permits ready insertion of the plug in place in the well pipe. The bore 79 is normally closed at its top in use by a flap valve 80 as in Figure 9 so that no cement deposited in the casing above, can affect the previously cleansed assembly below the protector 77. When the cement thereabove is subsequently drilled out the drill will remove valve 80, leaving the bore 79 open for a fishing spear by which the plug 77 may be readily withdrawn. It is to be understood, however, that instead of flap valve 80 as in Figure 9, a ball valve 80' may be used as seen in Figure 12. Upon withdrawal of the protector plug 77 the anchoring mecha-

nism and cementing valve assembly as a unit are in condition for ready retrieving in the manner to be now described.

After the setting of the cement the anchoring mechanism and cementing valve assembly as a unit, previously washed clean of cement and standing free thereof above the flap valve 28, is ready to be retrieved by lowering the retriever with its parts in the position of Figure 8, as they were before assembled for the lowering of the apparatus in the first instance, in the manner previously described. This time, however, the pilot stem 65 is detached from the spear head 63 and the latter enters the upper end of barrel 46 with clutch sleeve 66 resting thereon so that its lower balls 68, receding in shank groove 71, freely pass into the barrel.

When the upper balls 67, which at this time are extended by reason of being opposite the shank rib 72, arrest downward movement of the clutch sleeve, by engagement with the upper end of barrel 46, the shank continues downwardly in, and with respect to, said sleeve until its rib 72 passes below the balls 67 whereupon the latter can recede into the shank groove 70 and thus permit the clutch sleeve to pass completely into the barrel.

The retriever will thus be fully engaged with the anchoring mechanism and cannot be withdrawn as long as clutch sleeve 66 is loose on the lower reduced shank 62 of the clutch stem 60, since in any upward movement of said stem, the shank will be first drawn upwardly through the sleeve until its rib 72 is opposite the upper balls 67 and the latter will therefore catch the internal shoulder 53 of the barrel.

After the retriever is thus lowered into, and clutched with, the barrel 46, upward movement of line 54 serves to initially raise said barrel, withdrawing its tapering lower or expanding portion 45 from within the upper slips 44 so that the latter are free to retract from engagement with the casing. As the barrel 46 continues upwardly its lower shoulder 50 engages the head 49 of the mandrel extension 43 and raises this extension as well as the coupling 40 and mandrel 34. The result is that pressure is relieved from the packing 41, permitting the latter to loosen from the casing, and the lower external shoulder 39 of mandrel 34 engages the lower end of the lower expander 38 and raises the latter from within the lower slips 37 so that these slips may retract from the casing. At the same time the mandrel raises box 26 and relieves pressure on the packing 27 around the body 23 permitting this packing to loosen from the casing. Both sets of slips being thus permitted to retract, and both packings permitted to loosen, during steady upward movement of the retriever, the entire assembly is in condition for withdrawal except for the breaking free of the lower portion of the cementing valve assembly if there is cement therein below the flap valve 28.

In case there is cement in the lower portion of the cementing valve assembly, it is but a matter of breaking the thin fillets thereof between the slips of the boot end 33, and the jar included in the retriever may be used as an effective means of accomplishing this purpose, as well as in the loosening of any of the parts of the anchoring mechanism in case they tend to stick.

The entire assembly is then ready for withdrawal except for the possibility of sticking of the boot 31. As this is relatively soft rubber, the body 23 may be pulled out of the same since

pressure has been relieved on the boot holding flange 32, and the boot may be left in the casing as it presents no difficulties and may be very easily drilled up and circulated out.

In describing the foregoing operations considerable stress has been laid upon the particular construction of the anchoring mechanism and retriever whereby all of the running in and retrieving operations may be accomplished on a line, such as line 54. It must not be understood, however, that the use of a line is essential, because in some instances it may be more convenient to run the retriever in on tubing, drill pipe or sucker rods, and for certain purposes it may be especially advantageous to run in on tubing of drill pipe preparatory to retrieving after stage cementing in instances where sand may have accumulated around and within the upper end of the anchoring mechanism after withdrawal of the protecting plug 77.

In Figure 10, for example, the clutch stem 60', shank 62' and spear head 63' are shown with an axial bore 81, or in other words, are hollow. In this instance clutch stem 60' slides through packing 82 in the lower internally shouldered end 83 of a jar sleeve 84 attached at its upper end to tubing or drill pipe 85 in a manner presenting an upper internal shoulder 86. The upper head 87 of stem 60' may be engaged by either of the shoulders 83 and 86 and is preferably provided with wall apertures in the sleeve to prevent the entrapping of pressure between these parts in their relative movements. The clutch parts, including clutch sleeve 51, clutch balls 67 and 68 and spring fingers 69 may all be the same as previously described since the use of a hollow retriever, providing for the passage of cleaning fluid and pressure therethrough, in no way modifies the previously described engaging and disengaging operations for run in and retrieving.

With the hollow retriever, however, after detachment of the pilot stem 65 from spear head 63', a short tubular stem 88 is attached to said spear head to be run into the mandrel extension 43. This stem 88, as also shown in Figure 10, may have a packing ring 89 therearound intermediate its ends to snugly engage the internal surface of mandrel extension 43 to thus effectively establish circulation through the openings 42 and 47 of coupling 40 and the mandrel extension for thoroughly cleaning those portions of the anchoring mechanism above packing 41, before the anchoring mechanism is released for removal.

Similarly the tubular stem 88 may be used if it is desired to clean the interior of the anchoring mechanism and circulate accumulated sand and cuttings from the casing thereabove, by extending the said stem into the mandrel extension 43 without a packing ring 89 thereon. For this purpose the upper end or head 49 of said mandrel extension 43 may, as shown at the upper portion of Figure 11, have a packing 90 therearound sealing in a substantial manner against the inner surface of barrel 46. Likewise barrel 46 may have a packing ring 91 around the upper portion thereof to substantially seal against the internal surface of casing B. Thus no sand or cuttings can fall between the barrel and the casing, and any packed sand or cuttings within the mandrel extension may be washed out prior to engagement of the retriever with the anchoring mechanism to thus avoid the danger of further packing any accumulations of sand and cuttings in the latter.

In the above manner the anchoring mechanism

may be cleaned internally and then released and removed by the retrieving tool.

Various changes may be made in the details thus far described, and among these may be mentioned the fact that the protector plug 77 may be fixed in relation to, and run in with, the anchoring mechanism where the latter is used as a bridge, it being particularly noted that when so used, the protector plug adapts its valve 88 or 80' to cooperate with the back pressure valve 28 in preventing pressure from passing into the anchoring mechanism from above and below the same.

Reference has also been plainly made to the use of the anchoring mechanism and cementing valve assembly as a plug or bridge for operations thereabove in stage cementing, by leaving the same in the casing as a cement retainer after a cementing operation below the same. In some instances it may be desirable to use the same as a plug or bridge for a cementing operation thereabove where no cementing operation is contemplated therebelow and it is obvious that in such instances I may use only the anchoring mechanism itself as in Figure 11 down to and including the bushing 34' at the lower end of the mandrel 34, and utilize this bushing 34' to support a simple flap type of back pressure valve 28'. Thus the cementing valve assembly previously described with its packing 27 and the boot 31 may be eliminated since they are not necessary in this use as a mere plug or bridge, in which use the anchoring mechanism is to be protected from the cement thereabove by the valved protector plug 77 of Figures 9 and 12 as previously described.

In thus providing a cementing apparatus capable of ready retrieval and of employment as a cement retainer and a casing plug or bridge usable at various levels in a well, the present invention obviously effects great saving in time, trouble and waste of material and tools in connection with cementing operations, and is, in these respects an economical advance in the art. Moreover the invention effects a great saving in labor in avoiding the usual cleaning up and drilling out of extensive apparatus after each cementing operation has been completed.

The present application, as to all features thereof, is a substitute for application Ser. No. 339,483, filed June 8, 1940, and which became abandoned April 16, 1941.

Having thus fully described the invention, what is claimed is:

1. In a well cementing apparatus, a member selectively positionable in a well and having a passage therethrough and a back pressure valve closing said passage, packing means around said member, a cementing tube communicating with said passage of the member for discharging cement into the well bore below said member, and an elastic boot around the lower portion of said member having a normally closed yieldable section through which cement may be forced below the member.

2. In a well cementing apparatus, a well packer assembly adapted to be selectively positioned in a well and having a passage lengthwise therethrough, said assembly also having a back pressure valve for closing the passage thereof and packing means for sealing between the assembly and a well casing, a cementing tube movable freely through the assembly passage for engaging and holding said valve open to establish circulation through said passage, means carried by the as-

sembly and the tube for closing the passage when said back pressure valve is closed, and cement cut-off means at the lower end of the assembly below and independent of the back pressure valve.

3. A well cementing apparatus including, a well packer assembly adapted to be positioned in a well and having a passage lengthwise therethrough, a boot support carried by the assembly below the same having a lengthwise passage therethrough alined with the assembly passage, a cement tube movable through the passages of the assembly and the boot support, and an elastic boot depending from said support having a separable lower end for the passage of the tube therethrough which boot is self closing when said tube is retracted therefrom.

4. A well cementing apparatus including, a tubular body, a pair of spaced slip members surrounding said body, means carried by the body for expanding said slip members, an external packer carried by the body between the slip members, a tubular member carried by the lower end of the body, a back pressure valve hinged within the tubular member, a boot on the lower end of the tubular member below the valve, and a cement tube
